UNITED STATES PATENT OFFICE

2,590,712

STEAM GENERATOR WITH DOUBLE OUTLET FURNACE

Joseph A. Lacerenza, New York, N. Y., assignor to
Combustion Engineering-Superheater, Inc., a
corporation of Delaware

Application April 22, 1948, Serial No. 22,643

11 Claims. (Cl. 122—479)

1

This invention relates to improvements in steam generators and particularly to steam generators provided with superheaters and reheaters and having improved means for regulating the temperatures of the steam leaving said heaters.

High capacity steam generators working at high pressures and delivering steam at high temperatures may have a major portion or all of the steam returned to be reheated in the steam generator to a high temperature. For example, if the steam is delivered to a steam turbine at a temperature such as about 950° F. a major portion, such as about 90%, may be returned from an intermediate stage of the turbine to the steam generator to be reheated to a high temperature, such as about 950° F., and thence returned to the subsequent stages of the turbine.

When in such a generating plant the superheater and reheater are placed within the steam generator in series with respect to the gas flow through the generator, and with all of the gas flow flowing over both heaters, the reheat temperature will be too high at the high loads, if the reheater is designed to provide the proper temperature at the lower loads, or it will be too low at the low loads if the reheater is designed to provide the proper reheat at the higher loads.

To correct these departures from the desired steam temperatures by means of by-passing some of the gases around either of the heaters involves more than necessary heat absorbing surface in said respective heaters and additional heat absorbing surface to reduce the excess temperature of the by-passed gases.

When the superheater and reheater are placed in parallel passes for the furnace leaving gases, the relative amounts of gas flowing over the heaters may be shifted from one pass to the other in accordance with the heat requirements of the heaters, whereby the above mentioned objections may be substantially overcome.

It is an object of this invention to provide in a high capacity steam generator having steam heating surfaces within parallel passes for the furnace leaving gases, novel arrangements of fuel burning means and heat absorbing surfaces to more efficiently regulate the temperature and flow of said gases through said passes for superheating and reheating the steam from the generator to its proper temperatures.

Additional objects of the invention will appear from the following description of one preferred embodiment of the invention when taken in conjunction with the accompanying drawings wherein:

2

Figure 1 is a diagrammatic vertical section through a steam generator embodying the invention;

Figure 2 is a cross section taken on line 2—2 of Figure 1;

Figure 3 is a cross section taken on line 3—3 of Figure 1; and

Figure 4 is a fragmentary vertical section through a typical burner of the tilting type.

10 Figure 5 is a diagrammatic illustration of a superheater with a desuperheater arranged in the steam line to the prime mover.

As illustratively shown in Figure 1 my improved steam generator comprises a furnace which may

15 include three zones generally designated as A, B and C. At the top of the furnace is an outlet U and at the bottom of the furnace another outlet L. The furnace may be provided with two sets of burners, an upper set 1 and a lower set

20 2. Preferably the burners are of the tilting type as disclosed in the U. S. Patent to Kreisinger et al.

No. 2,363,875. The upper set of burners 1 may

be arranged to be tilted independently of the

lower set of burners 2.

25 Preferably the furnace is completely lined on all sides with steam generating tubes 3 which are connected for circulation of water therethrough to the steam and water drums 4 and 5 via risers 6, 7 and 8. Risers 6 and 7 connect

30 respectively the front and rear walls of the furnace to drum 4 while risers 8 connect the side walls through headers 9; there being two headers 9, one for each side wall. A multiplicity of downcomer tubes 10 connect the steam drums 4 and

35 5 to headers 11 and 12 from which the downcomer tubes 13 and 14 carry water from the drums to the bottom headers 15, 16, 17, 18 and 19 of the water walls. There are similar headers 15, 17 and 19 for the side wall opposite that

40 shown.

The offtakes U and L direct the gases leaving the furnace into two passes 20 and 21. Upper pass 20 is provided with an outlet 22 while lower pass 21 is provided with an outlet 23. Preferably said outlets 22 and 23 are adjacent one another and are provided with dampers 24 and 25 for throttling gas flow therethrough.

45 Preferably the passes 20 and 21 have walls lined with steam generating tubes connected into circulation with the steam drums 4 and 5. Adjacent the offtake U some of the water wall tubes 3 extend in an upwardly sloping direction into the furnace and thence bend upwardly and outwardly from the furnace to form the bottom of pass 20 at the furnace offtake end U. These tubes 3 connect into a header 26 from which risers

7a extend via risers 7 into drum 4. The horizontal portions of these risers 7 serve as a support for the roof 27 of the furnace and for the upper end of the pass 20. The remaining of the water wall tubes 3 may pass upwardly across offtake U and join risers 7 into the drum 4.

Adjacent the lower offtake L of the furnace some of the water wall tubes 3a rise from header 18 upwardly and rearwardly along the bottom of pass 21 thence rise in open formations across the pass, thence extend forwardly toward the furnace while supporting the upper wall of the pass, and thence rise in alignment with the remaining tubes 3 of the rear wall of the furnace. The remaining tubes 3a from header 18 rise vertically across offtake L and join the former tubes 3 in alignment with the rear wall of the furnace.

The walls of the vertical portion of passes 20 and 21 are preferably lined with steam generating tubes which are supplied from the bottom headers 18 and 28. The tubes 29 rising from header 28 extend upwardly adjacent the front wall of pass 21 for a short distance, thence some of the tubes 29 extend into the pass and upwardly to form a by-pass 30. Above by-pass 30 the tubes 29 adjacent the front wall extend inwardly to join the remaining tubes and thence continue upwardly in alignment again along the front wall of pass 21 and up into pass 20. After passing upwardly for a distance in pass 20 said tubes 29 again spread apart into a lower group 31 and an upper group 32 forming the walls of a by-pass 33. At the upper end of said by-pass 33 the lower group of tubes 31 bend upwardly to cross the by-pass 33 and connect to header 26. They discharge through risers 7a, 7 to the steam drum 4. At the upper end of said by-pass 33 the upper group of tubes 32 bend upwardly as tubes 32a across the pass 20 and thence continue to discharge into drum 5. By-passes 30 and 33 are provided with dampers 30a and 33a.

The rearward sides of passes 21 and 20 are lined with tubes 34 which are continuations of tubes 35 rising from header 18 and extending across pass 21 to the rear wall thereof. Thence tubes 35 continue upwardly as tubes 34 through both the passes 21 and 20 and at their upper ends bend forwardly to form the roof tubes 36 of pass 20. The upper ends of said roof tubes 36 bend upwardly and thence continue as tubes 36a into drum 5.

Within the upper portion of pass 20 is a superheater divided into three sections 37, 38 and 39. Steam from drum 5 is conveyed via tubes 40 into the superheater inlet header 41 whence it flows serially through sections 37, 38 and 39 to superheater outlet header 42.

The superheater sections 37, 38 and 39 may constitute the entire superheater surface required. Should more superheat be required than can be efficiently provided by these sections, it may be desirable to locate a further superheater section 43 within the lower portion of pass 21 which receives the steam from outlet header 42 via connection 44 into its inlet header 45. Steam leaves superheater 43 via outlet header 46.

Adjacent said superheater 43 and located within the lower portion of pass 21 is a portion of a re-heater 47 the remaining portion 48 of which is located within the vertical portion of pass 21. Steam from an intermediate expansion stage of a prime mover, such as a steam turbine, is conducted to the inlet header 49 of the re-heater by a conduit not shown, thence passes downwardly through re-heater 48 comprising a bank of sinuous

tubes and connected to the sinuous tube bank of re-heater portion 47 via tubes 50. Steam leaves the re-heater 47 via outlet header 51 to be returned to a later stage in said prime mover.

Within the vertical portions of passes 21 and 20 and adjacent the outlets 23 and 22 thereof is located an economizer having lower and upper sections 52 and 53 respectively. Feed water enters the lower portion of lower economizer section 52 thence flows upwardly through the tubes of the economizer into the lower portion of the upper section 53 thence upwardly through that section and out of the top thereof into the drum 4 through connections not shown.

Figure 2 shows one preferred arrangement of the burners 1 and 2 with respect to the furnace, located adjacent or at the corners thereof. The fuel streams issuing from each set of these burners are directed tangentially toward the surface of an imaginary vertically disposed cylinder within the furnace and may selectively be directed upwardly and downwardly as taught by Kreisinger et al. Patent 2,363,875 earlier identified.

Referring to Figure 1, the groups of burners 1 and 2 are preferably connected each group to one mill 54 or mill 55, or sets of separate mills, and the fuel is delivered from the mills through conduits 56, 57 to fans 58, 59 and thence via conduits 60, 61 to the groups of burners 1 and 2 respectively. Only two mills are shown by way of example, each connected to one set of burners. Obviously the remaining burners are similarly connected although not so shown. By such grouping of mills and burners, the amount of fuel delivered by burners 1 may be varied from that delivered by burners 2 by regulating the fuel output of the respective mills by controlling the speed of each mill motor M1 and M2. In the illustrative embodiment shown in Fig. 1 a speed adjuster S1 is interposed in the line between the power source and mill motor M1. Similarly a speed adjuster S2 is interposed in the line between the power source and mill motor M2. Each motor drives its respective mill 54 or 55 as well as fan 57 or 58 which delivers the fuel to the burner 1 or 2 respectively.

Figure 3 is a plan section through the furnace and the upper pass 20 showing the superheater sections 37, 38 and 39 within said pass. Preferably the by-pass 33 extends for the full width of the pass 20, as this drawing view shows.

Figure 4 shows a typical fragmentary sectional view through one of the burners. It comprises an air casing or housing 62 and pulverized fuel nozzle 1, 2 extending therethrough. Only one such fuel nozzle is shown in this disclosure. The fuel nozzle comprises a conduit 63 which is provided with an end piece or tip 64 rotatable vertically about horizontal supporting bearings 65 on the end of conduit 63. The tip 64 and conduit 63 may be formed at their juncture to a socket type of joint as shown.

Surrounding the nozzle tip 64 and mounted thereon is a tubular air deflecting vane 66, the whole when tilted upwardly or downwardly, directing the fuel and air stream accordingly into the furnace. The tip 64 and vane 66 are rotated by means of a rod 67 connected at one side of the tip by an arm 68 fixed to the pin of bearing 65 on which the tip 64 rotates. The other end 70 of rod 67 is connected to a bell crank 68 which is connected to a vertically movable member 69. When the vertical member 69 is moved upwardly or downwardly it tilts the burner either downwardly or upwardly.

Above and below each of the fuel pipes there

are provided air chambers 70 having tips 71 which rotate upwardly and downwardly together with the fuel nozzles 64 and through the same angularity. The tips 71 are pivoted at 72 and connected by rod 73 to the end of the bell crank 74 similar to the bell crank for operating the fuel nozzles, the bell crank 74 being in turn connected to the vertically movable member 69.

According to the invention the steam generator is provided with two parallel passes with respect to the flow of furnace leaving gases, one pass 20 being connected to an offtake U adjacent one end of the furnace and the other pass 21 being connected to an offtake D adjacent the other end of the furnace. One or more heaters are placed within each of these passes as already described, the heaters absorbing relatively variable amounts of heat from the gases in order to heat the respective fluids passing through them to the proper temperatures at the various ratings of the steam generator. To meet these variations in heat absorption, the amount of gases flowing through each pass 20 and 21 is varied and/or the entering temperature of the gases to each of the passes is varied, supplemented by the control dampers in each of the passes.

The heat in the furnace leaving gases entering each pass 20 and 21 may be regulated by varying the amounts of fuel delivered by the various burners to the furnace. By varying the fuel delivered by the mills 54 associated with the upper burners 1, the heat flowing into the upper pass 20 with the gases may be varied to suit and by varying the fuel delivered by the mills 55 associated with the lower burners 2, the heat flowing into the lower pass 21 may be varied to suit.

The temperature of the furnace leaving gases may also be varied by tilting the burners by means disclosed in the U. S. patent to Henry Kreisinger et al. No. 2,363,875. By tilting the upper burners 1 upwardly, the mass of flame therefrom will move into the upper portion of the furnace to zone B and consequently less heat will be absorbed from the flame by the portions of the furnace below the flame resulting in relatively hotter furnace leaving gases to the upper pass 20. By tilting the lower burners 2 downwardly to zone C the mass of flame from the fuel delivered by these burners will move into the lower portion of the furnace and less heat will be absorbed from said flame by the portion of the furnace above the flame, resulting in relatively hotter furnace leaving gases to the bottom pass. Should the upper pass require substantially more heat both the upper and lower burners may be tilted upwardly and should it require substantially less heat both the upper and lower burners may be tilted downwardly.

The flow of gases through the respective passes is controlled by dampers 24 and 25 to supplement the burner control. Obviously any combination of angularity of the burners may be used and/or any variations in fuel supply by the various burners may be used to obtain the desired steam temperatures of the steam leaving the respective heaters.

The by-passes 30 and 33 and the regulation of dampers 30a and 33a may serve to care for minor fluctuations in temperatures not covered by the manipulation of the burners and/or dampers 24 and 25. Furthermore desuperheating of the steam by means well known, such as desuperheater 80 (Fig. 1), may be employed to iron out small variations in steam temperatures leaving the heaters due to heat lag caused by the large mass of metal in the heaters. In the preferred

embodiment of my invention shown in Fig. 1 the desuperheater 80 is arranged between stages 37 and 38 of the superheater. In some cases, especially in cases where a single stage superheater is utilized as diagrammatically indicated in Fig. 5 a desuperheater 81 is located in the steam line connecting the superheater with the turbine. In other cases such as in connection with a reheat-superheater 41, 43, Fig. 1, a desuperheater 82 is preferably located in the steam line between the intermediate expansion stage of the steam turbine and the reheat-superheater. Each desuperheater 80, 81 and 82 is connected to a supply of spray water or cooling fluid (not shown) in a manner well known in the art.

By advantageously dividing the heaters and placing them within the two parallel passes with respect to gas flow a relatively lower resistance to gas flow may be obtained.

Should the resistance to gas flow through the heaters within the two passes 20 and 21 be materially different, the overall resistances may be substantially balanced by shifting some of the economizer heating surface from the pass of high resistance into the pass of low resistance.

Should the heat absorption from the gases by the heaters within the two passes 20 and 21 be materially different, the overall absorption of each pass may be substantially balanced by shifting some of the economizer heating surface from the pass of high heater absorption to the one of low absorption.

By placing the reheat-superheater and the second stage of the superheater in the bottom pass both will be located adjacent the operating floor at a level nearer the steam turbine which they serve and the superheater connection to the turbine will involve shorter high pressure and high temperature piping.

A further advantage is in having two sets of superimposed burners, the upper set burning one fuel whose products of combustion rise to flow into the upper furnace offtake and pass, and the lower set burning another fuel whose products of combustion flow downwardly into the lower furnace offtake and pass. In this manner the two flames and products of combustion of the separate fuels avoid being mixed. Such mixture may result in slag deposits on all of the heating surfaces, both upper and lower, if one of the fuels contains slag producing elements. By separating the flow of the products of combustion from each fuel according to the invention, the heating surfaces in the path of the products of combustion from the non-sludging fuel will remain free from slag. For example, such fuels as blast furnace gas or oil may be delivered to the upper set of burners while pulverized coal may be delivered to the lower set.

While the preferred embodiment of my invention has been shown and described, it will be understood that changes in construction, combination and arrangement of parts may be made without departing from the spirit and scope of the invention as claimed.

65 I claim:

1. In a steam generating unit having a generally vertical furnace associated therewith; steam generating tubes lining the walls of the furnace; a top offtake adjacent the upper end of the furnace and a bottom offtake adjacent the lower end of the furnace; means forming two passes for the flow of furnace leaving gases therethrough, the first of said passes being connected to said top offtake and the second pass being connected to said bottom offtake; damper means in

at least one of said passes adjustable to govern the apportionment between those two passes of the total gases leaving the furnace therethrough; at least one fluid heater arranged in each of said first and second passes; burner means located between said top and bottom offtakes in the furnace walls and arranged for delivering fuel and air to be burned into the furnace tangentially to an imaginary vertically disposed cylinder in said furnace; and means for tilting said burners for directing the fuel and air streams therefrom within the furnace toward said top offtake or toward said bottom offtake to vary the relative amount of heat absorbed by said steam generating tube portions in both the upper and lower portions of the furnace.

2. In a steam generating unit having an associated furnace; steam generating tubes lining the walls of the furnace; an offtake adjacent one end of the furnace and another offtake adjacent the other end of the furnace; means forming two passes for the flow of furnace leaving gases therethrough, the first of said passes being connected to one of said offtakes and the second pass being connected to the other offtake; dampers in said passes adjustable to govern the apportionment therebetween of the total gases leaving the furnace therethrough; a steam superheater and a steam reheater arranged one in each of said first and second passes; burner means located between said offtakes in the furnace walls and arranged for delivering fuel and air into the furnace to be burned therein; and means for tilting said burners for directing the fuel and air streams therefrom within the furnace either toward one offtake or toward the other offtake to vary the relative amount of heat absorbed by said steam generating tubes located in that part of the furnace which is adjacent to said one offtake and that part of the furnace which is adjacent to said other offtake.

3. In a steam generating unit having a generally vertical furnace associated therewith; steam generating tubes lining the walls of the furnace; an upper offtake adjacent the upper end of the furnace and another lower offtake adjacent the lower end of the furnace; means forming two passes for the flow of furnace leaving gases therethrough, the first of said passes being connected to the said upper offtakes and the second pass being connected to the said lower offtake; dampers in said passes adjustable to govern the apportionment therebetween of the total gases leaving the furnace therethrough; a first stage steam superheater arranged in said first pass and a second stage steam superheater plus a steam reheater arranged in said second pass; burner means located between said upper and lower offtakes in the furnace walls and arranged for delivering fuel and air into the furnace to be burned therein; and means for tilting said burners for directing the fuel and air streams therefrom upwardly within the furnace and toward said upper offtake or downwardly within the furnace and toward said lower offtake, to vary the relative amount of heat absorbed by said steam generating tube portions in the upper and lower portions of the furnace.

4. In a steam generating unit having an associated furnace; a steam and water drum; steam generating tubes lining the walls of the furnace connected for circulation to said drum; an upper offtake adjacent the upper end of the furnace and another lower offtake adjacent the lower end of the furnace; means forming two

passes for the flow of furnace leaving gases therethrough, the first of said passes being connected to the said upper offtake and the second pass being connected to the said lower offtake, the rearward portions of said passes with respect to gas flow therethrough being in substantial vertical alignment; steam generating tubes extending through both said rearward pass portions and lining the walls of said passes and connected for circulation to said drum; dampers in said passes adjustable to govern the apportionment therebetween of the total gases leaving the furnace therethrough; at least one steam superheater arranged in one of those passes and a steam re-heater arranged in the other; burner means located between said upper and lower offtakes in the furnace walls and arranged for delivering fuel and air into the furnace to be burned therein; and means for tilting said burners for directing the fuel and air streams therefrom upwardly within the furnace and toward the upper offtake or downwardly within the furnace and toward said lower offtake to vary the relative amount of heat absorbed by said steam generating tubes in the upper and lower portions of the furnace.

5. In a steam generating unit having an associated furnace; steam generating tubes lining the walls of the furnace; an upper offtake adjacent one end of the furnace and another lower offtake adjacent the other end of the furnace; means forming two passes for the flow of furnace leaving gases therethrough, the first of said passes being connected to the said upper offtake and the second pass being connected to the said lower offtake; dampers in said passes adjustable to govern the apportionment therebetween of the total gases leaving the furnace therethrough; at least one steam superheater arranged in one of those passes and a steam re-heater arranged in the other; means forming a by-pass for the flow of some of the furnace gases around at least one of said heaters; a damper in said by-pass for regulating said flow; burner means located between said two offtakes in the furnace walls and arranged for delivering fuel and air into the furnace to be burned therein; and means for tilting said burners for directing the fuel and air streams therefrom within the furnace upwardly and toward the upper offtake or downwardly and toward the lower offtake to vary the relative amount of heat absorbed by said steam generating tubes in the upper and lower portions of the furnace.

6. In a steam generating unit having an associated furnace; steam generating tubes lining the walls of the furnace; a top offtake adjacent the upper end of the furnace and a bottom offtake adjacent the lower end of the furnace; means forming two passes for the flow of furnace leaving gases therethrough, the first of said passes being connected to the said top offtake and the second pass being connected to the said bottom offtake; dampers in said passes adjustable to govern the apportionment therebetween of the total gases leaving the furnace therethrough; at least one fluid heater arranged in each of said first and second passes; upper and lower burner means located between said upper and lower offtakes in the furnace walls for delivering fuel and air into the furnace to be burned therein; and means for tilting said upper and lower burners for independently directing within the furnace the upper and lower fuel and air streams issuing therefrom upwardly and toward

said top offtake or downwardly and toward said bottom offtake to vary the relative amount of heat absorbed by the steam generating tube portions adjacent the top offtake and the steam generating tube portions adjacent the bottom offtake.

7. In a steam generating unit having an associated furnace; steam generating tubes lining the walls of said furnace; an offtake adjacent one end of the furnace and another offtake adjacent the other end of the furnace; means forming two passes for the flow of furnace-leaving gases therethrough, the first of said passes being connected to one of said offtakes and the second pass being connected to the other offtake; damper means in at least one of said passes adjustable to govern the apportionment therebetween of the total gases leaving the furnace therethrough; at least one fluid heater arranged in each of said first and second passes; burner means located between said offtakes in the furnace walls for delivering air and fuel into the furnace to be burned therein; and means for tilting said burners for directing the fuel and air streams therefrom within the furnace either toward one offtake or toward the other offtake, to vary the relative amount of heat absorbed by the furnace wall portion adjacent the said one offtake and the furnace wall portion adjacent the said other offtake.

8. In a steam generating unit having an associated furnace; a top offtake adjacent the upper end of the furnace and a bottom offtake adjacent the lower end of the furnace; means forming two passes for the flow of furnace-leaving gases therethrough, the first of said passes being connected to the said top offtake and the second pass being connected to the said bottom offtake; at least one fluid heater arranged in each of said first and second passes; at least two burners located in the furnace walls intermediate said upper and lower offtakes for there delivering air and fuel streams into the furnace, the aforesaid fuel and air from each individual burner creating a mass of high temperature burning gas within the furnace interior; individual tilting means for each of said burners for independently directing the fuel and air stream issuing therefrom either upwardly within the furnace and toward said top offtake or downwardly within the furnace and toward said bottom offtake so as to bring the location of each burner-produced mass of burning gas within the furnace walls either closer to said top offtake and more remote from said bottom offtake or closer to said bottom offtake and more remote from said top offtake and, by reason of the velocity head created by said tilted up or tilted down stream of air and fuel from each burner, to increase the gas pressure adjacent the particular offtake towards which each burner is tilted and thereby cause the gas flow through that offtake correspondingly to increase; and steam generating tubes lining the walls of said furnace for absorption of heat from each of said burner-produced masses of high temperature gas, the quantity of heat so absorbed by said wall-lining tubes from each of said burner-produced masses of high temperature gas varying with the vertical location of that gas mass within the furnace whereby the aforesaid tilting of each furnace burner alters the total heat leaving both the top and the bottom furnace offtakes and varies both the quantity and the temperature of the gases leaving said top offtake and of the gases leaving said bottom offtake thereby to control the heat absorbed by each of the aforesaid fluid heaters in said top and bottom offtake passes.

9. In a steam generating unit having an associated furnace; an offtake adjacent one end of the furnace and another offtake adjacent the other end of the furnace; means forming two passes for the flow of furnace-leaving gases therethrough, the first of said passes being connected to the said one offtake and the second pass being connected to the said other offtake; at least one superheater arranged in each of said first and second passes; burner means located in the furnace walls intermediate said two offtakes for there delivering into the furnace streams of fuel and air creating a mass of high temperature burning gas within the furnace interior; means for tilting said burner means to direct said fuel and air streams issuing therefrom either toward the furnace's said one offtake or toward the furnace's said other offtake so as to bring the location of said high temperature mass of burning gas within the furnace walls either closer to said one offtake and more remote from the other offtake or closer to said other offtake and more remote from said one offtake and, by reason of the direction given by said burner tilt to the velocity head inherent in said streams of air and fuel from the burner means, to increase the gas pressure adjacent the particular offtake towards which the burner means is tilted and thereby cause the gas flow through that offtake correspondingly to increase; steam generating tubes lining the walls of said furnace for absorption of heat from said mass of high temperature gas, the quantity of heat so absorbed by said wall-lining tubes varying with the location of said high temperature gas mass within the furnace along the length thereof between said one end offtake and said other end offtake whereby the aforesaid tilting of said burner means alters the total heat leaving both the one and the other furnace offtake and varies both the quantity and the temperature of the gases leaving said one offtake and of the gases leaving said other offtake thereby to control the heat absorbed by each of said superheaters in the said one and other offtake passes; and desuperheater means associated with at least one of said superheaters to effect final control in the temperature of steam passed therethrough.

10. In a steam generating unit having an associated furnace; an offtake adjacent one end of the furnace and another offtake adjacent the other end of the furnace; means forming two passes for the flow of furnace-leaving gases therethrough, the first of said passes being connected to the said one offtake and the second pass being connected to the said other offtake; at least one fluid heater arranged in each of said first and second passes; burner means located in the furnace walls intermediate said two offtakes for there delivering into the furnace a stream of combustible mixture creating a mass of high temperature burning gas within the furnace interior; means for tilting said burner means to direct said stream of combustible mixture issuing therefrom either toward the furnace's said one offtake or toward the furnace's said other offtake so as to bring the location of said mass of burning gas within the furnace walls either closer to said one offtake and more remote from the other offtake or closer to said other offtake and more remote from said one offtake and, by reason of the direction given by said burner tilt to the velocity head inherent in said stream of combustible mixture, to increase the gas pressure adjacent the particular offtake towards which

the burner means is tilted and thereby cause the gas flow through that offtake correspondingly to increase; means for varying the quantity of the combustible mixture being discharged from said tiltable burner means whereby to vary the velocity head and gas pressure in said gas mass as well as the quantity of gas flowing through each of said offtakes; and steam generating tubes lining the walls of said furnace for absorption of heat from said mass of high temperature gas, the quantity of heat so absorbed by said wall-lining tubes varying with the location of said high temperature gas mass within the furnace along the length thereof between said one end offtake and said other end offtake whereby the aforesaid tilting of said burner means alters the total heat leaving both the one and other furnace offtakes and varies both the quantity and the temperature of the gases leaving said one offtake and of the gases leaving said other offtake thereby to control the heat absorbed by each of said fluid heaters in the said one offtake and said other offtake passes.

11. In a steam generating unit having an associated furnace; an offtake adjacent one end of the furnace and another offtake adjacent the other end of the furnace; means forming two passes for the flow of furnace-leaving gases therethrough, the first of said passes being connected to the said one offtake and the second pass being connected to the said other offtake; at least one fluid heater arranged in each of said first and second passes; burner means located in the furnace walls intermediate said two offtakes for there delivering into the furnace a stream of combustible mixture creating a mass of high temperature burning gas within the furnace interior; means for tilting said burner means to direct said stream of combustible mixture issuing therefrom either toward the fur-

nace's said one offtake or toward the furnace's said other offtake so as to bring the location of said mass of burning gas within the furnace walls either closer to said one offtake and more remote from the other offtake or closer to said other offtake and more remote from said one offtake and, by reason of the direction given by said burner tilt to the velocity head inherent in said stream of combustible mixture to increase the gas pressure adjacent the particular offtake towards which the burner means is tilted and thereby cause the gas flow through that offtake correspondingly to increase; and steam generating tubes lining the walls of said furnace for absorption of heat from said mass of high temperature gas, the quantity of heat so absorbed by said wall-lining tubes varying with the location of said high temperature gas mass within the furnace along the length thereof between said one end offtake and said other end offtake whereby the aforesaid tilting of said burner means alters the total heat leaving both the one and the other furnace offtakes and varies both the quantity and the temperature of the gases leaving said one offtake and of the gases leaving said other offtake thereby to control the heat absorbed by each of said fluid heaters in the said one offtake and said other offtake passes.
